WILLIAM A. L. SCHAEFER, OF CHICAGO, ILLINOIS, ASSIGNOR TO JOINTLESS FIRE
BRICK COMPANY, OF CHICAGO, ILLINOIS, A CORPORATION OF ILLINOIS.

METHOD OF MAKING PACKAGES.

Application filed August 15, 1921. Serial No. 492,270.

To all whom it may concern:

Be it known that I, WILLIAM A. L. SCHAEFER, a citizen of the United States, residing at Chicago, in the county of Cook and State of Illinois, have invented a certain new and useful Improvement in Methods of Making Packages, of which the following is a full, clear, concise, and exact description, reference being had to the accompanying drawings, forming a part of this specification.

My invention relates to containers and the method of making the same, and is concerned particularly with containers for cementitious material such as plastic fire brick.

Containers entirely of wood, by reason of their liability to breakage in the course of transportation are not adapted for materials of the weight and nature of plastic brick.

Moreover, when such wooden containers are employed, I find that the material dries out and does not reach the consumer in proper condition. While a container entirely of sheet metal will keep the material in excellent condition, such containers have been impractical and have not come into use for the purpose indicated because of their inability to hold against bulging and other distortion when filled, without expensive

construction and reinforcements, and, since the containers are used once and discarded, such expense is prohibitive. A container for the purposes for which the container of my invention is provided must be provided at a comparatively low cost. A container too expensive to be discarded after one shipment makes collecting and reshipping of the empty container necessary, the cost of which renders the use of the container prohibitive.

The object of my invention is the provision of a novel, simple and inexpensive container which will keep the material in excellent condition from the time it leaves the factory until it reaches the consumer, and which will not bulge or become otherwise distorted, but will hold up when filled. In addition to the aforesaid functional advantages and structural superiorities, I aim to provide a container which may be so cheaply made up and packed that after being used once, it may be discarded without appreciable loss.

I accomplish the objects of my invention by the provision of a container comprising

a cylindrical sheet metal shell having 55 wooden end members held together by nails anchored in the contents to form a complete package. The sheet metal shell keeps the material in excellent condition, while the wooden end members provide the necessary 60 stiffness so that the shell will hold against bulging and such other distortion as has rendered containers entirely of sheet metal impractical for the purpose indicated. The relative dimensions of the sheet metal shell 65 and the wooden end members are such that the condition maintaining qualities of the shell are not impaired. The originally loose material, of course, tends to cake, and at the ends, where it is in contact with the wood, 70 forms quite a hard crust and it is in this crust that the nails are anchored.

In addition to the advantages already set out, construction of the container is facilitated by reason of the combination of the 75 sheet metal shell with the wooden end members and certain advantageous details of construction are made possible.

My invention contemplates a novel method whereby this desirable package is produced, 80 and this method is made the subject matter of the appended claim.

In the accompanying drawings:

Figure 1 is a perspective view showing the piece of sheet metal employed in making up a container in accordance with my practice of my invention and the step of forming the same into the shell portion thereof;

Figure 2 is a fragmentary perspective 90 view showing one of the wooden end members inserted into the shell;

Figure 3 shows the step of securing the wooden end member in place;

Figure 4 shows the step of arranging the 95 opposite end in place;

Figure 5 is a fragmentary perspective view of the completed container; and

Figure 6 is a fragmentary vertical sectional view taken substantially on the line 100 6-6 of Figure 5.

A piece of suitable sheet metal 1 of such dimensions that it may be rolled or otherwise formed into the uniform cylindrical shell 2 is the basis of the formation of the 105 container. The adjacent longitudinal edges of the shell 2 are joined along the seam 3 as by bending or lapping them back into

cooperative engagement as shown at 4 or in any other suitable manner.

A suitable wooden end member or bottom 5 is then arranged in one end of the shell 2 being spaced in from the end of the shell substantially as shown. That portion of the shell projecting outwardly beyond the end member 5 is provided with a plurality of slashes or cuts 6 extending outwardly from 10 the end member 5 to the adjacent end of the shell 2. These slashes or cuts provide a plurality of flap or tab portions 7 which flap portions 7 are bent in along the outer face of the end member 5 and nailed or 15 otherwise suitably secured thereto.

The cuts or slashes 6 are preferably at an angle as shown in Figure 3 so that when bent in along the outer face of the end member 5 one corner of each of the flap portions 20 7 will overlap the adjacent corner of the adjacent flap portion. When the overlapping corners are secured to the end member, as by means of the nails 9, the adjacent corners of the adjacent flaps are 25 securely held thereby. The nails 9, 9, are preferably of such length as to extend through and beyond the end 5.

A groove or bead 8 in the shell 2 extending circumferentially around the edge of 30 the end member 5 serves the dual purpose of reinforcing the end of the container and holding or retaining the end 5 in place until final attachment to the shell 2 is effected. This bead also serves as a limiting 35 circle for determining the line on which to fold the flap portions 7 and limits the folding line of all flap portions to a common height for producing a smooth planar end on the container. The bead 8 may be omitted and the end 5 otherwise held in place as by means of a form or by inverting the 40 container upon a post or the like until final attachment is effected. Similar circumferential grooves or beads 10 may be provided to strengthen the shell within its length. The cuts or slashes 6 may be provided in the sheet metal at any desired stage in the 45 formation of the container. They may be provided for example, before rolling or forming the sheet metal into the shell 2, or even after insertion of the end piece 5. The grooves or beads may likewise be provided in the sheet metal at any desired stage in the formation of the container, but the 50 end grooves or beads 8 are preferably formed before the flap portions 7 are bent.

The end 5 being secured in place, the container is ready for the reception of the plastic fire brick or other material to be packed therein. In the case of plastic fire brick, for example, the loose material is packed into the container up to the level at 60 which it is desired to position the end member or cover 11. The end member 11 is then laid firmly upon the contents in the 65

open end of the shell 2, which end like the opposite end of the shell is provided with a plurality of slashes or cuts 12. The inward crimp of the adjacent end bead 8 preferably assists in positioning this end member at right angles to the length of the shell and firmly holds the end member in place. If desired this bead or crimp in the shell can be formed after the insertion of the end member to partly compress the 70 crimp into the wood. The flap or tab portions 13 provided by the slashes or cuts 12 are bent in along the outer face of the end member 11 and along the limiting circle formed by the bead 8 and are nailed as 75 shown at 14 or otherwise suitably secured thereto. Nails are preferably employed and the shanks thereof preferably extend through the end member and into the plastic material 20, as shown in Figure 6, to 80 form an anchoring connection between the container and the material which will not interfere with the convenient removal of the material from the container. The end (Figure 6) of the contents 20 packed in the 85 container becomes hardened to protect the material inside it and provides admirable anchoring means for the nails 14. The material is removed by simply chopping the 90 container open.

As illustrative of the relative dimensions of a commercially practicable container which I at present construct I employ No. 24 gauge sheet metal for the shell. For this thickness of metal I employ wooden end 95 members of $\frac{1}{4}$ inch thickness. The container is substantially 18 $\frac{1}{2}$ inches across and 34 inches in length. It will be noted that with this relatively light gauge of sheet metal it is imperative that a relatively thick, rigid 100 end member be employed to preserve the cylindrical form and prevent bulging at the ends. This the wooden end members provide at scarcely appreciable cost and with the added advantage of affording a 105 convenient and inexpensive manner of securing the sheet metal shell to the end heads.

I claim:

The method of making a package comprising filling an open top closed bottom container with loose material to a level near the top thereof, supporting a cover on said material within the margin of said container above said level, bending the top peripheral margin of said container inwardly over said cover, and driving fastening means through said margin into said cover, utilizing said material to support said cover while said fastening means are being so 115 driven in.

In witness whereof, I hereunto subscribe my name this 6 day of August, 1921.

WILLIAM A. L. SCHAEFER.
